FISH FINDER OR SIMILAR ARTICLE

Thomas F. Sarah, Akron, Ohio, assignor to The Enterprise Manufacturing Company, Akron, Ohio, a corporation of Ohio

Filed Aug. 23, 1961, Ser. No. 66,464

Term of patent 14 years

(Cl. D52—6)

FIG. 1 is a side elevation of a fish finder embodying my new design.

FIG. 2 is a front elevation thereof.

FIG. 3 is a top plan view thereof with the bottom portion removed for convenience of illustration.

FIG. 4 is a bottom plan view thereof with the top part removed for convenience of illustration.

I claim:

The ornamental design for a fish finder or similar article, substantially as shown.
